(57) **CLAIM**

The ornamental design for a solar module, as shown and described.

DESCRIPTION

FIG. 1 is a front perspective view of a solar module embodying my new design;

FIG. 2 is a front elevational view thereof;

FIG. 3 is a rear elevational view thereof;

FIG. 4 is a side elevational view thereof; and,

FIG. 5 is top plan view thereof, the bottom plan view being a mirror image.

The broken lines showing are for illustrative purposes and form no part of the claimed design.
